(57) **CLAIM**

The ornamental design for a fingertip cover, as shown and described.

DESCRIPTION

FIG. 1 is a front elevation view of a fingertip cover showing my new design;

FIG. 2 is a rear elevation view thereof;

FIG. 3 is a right side elevation view thereof, the opposite side being a mirror image of the shown;

FIG. 4 is a top plan view thereof;

FIG. 5 is bottom plan view thereof; and,

FIG. 6 is an isometric view thereof.

1 Claim, 5 Drawing Sheets(56)
